C. F. ROBINSON.

ARTICLE HOLDER.

APPLICATION FILED JUNE 16, 1920.

1,367,503.

Patented Feb. 1, 1921.

UNITED STATES PATENT OFFICE.

CLYDE F. ROBINSON, OF MIAMI, OKLAHOMA.

ARTICLE-HOLDER.

1,367,503.

Specification of Letters Patent.

Patented Feb. 1, 1921.

Application filed June 16, 1920. Serial No. 389,473.

To all whom it may concern:

Be it known that I, CLYDE F. ROBINSON, a citizen of the United States, residing at Miami, in the county of Ottawa and State 5 of Oklahoma, have invented certain new and useful Improvements in Article-Holders, of which the following is a specification, reference being had to the accompanying drawings.

10 This invention relates to article holders and particularly to a holder for holding implements such as ice picks.

An object of the invention is to provide a device of this character capable of being 15 attached to an ice chest or like support for holding one or more ice picks within convenient reach of the user.

Another object is to provide a device of this character which in addition to providing 20 pockets for the reception of ice picks also provides a pocket for bills or ice coupon books.

Another object of the invention is to provide a device of this character formed from 25 a blank sheet of material having its opposed edges rolled upon said sheet to provide pockets, said rolled portions holding the sheet in spaced relation to a support to provide a pocket between the first mentioned 30 pockets.

A still further object of the invention is to provide a device of this character having its opposed marginal edges rolled upon the sheet in conical formation so as to provide 35 pockets which correspond to the shape of an ice pick, and which also permits one edge of the sheet to engage a support to provide a bottom for a third pocket large enough to receive a coupon book or like article.

40 With these and other objects in view, the invention consists in the improved construction and arrangement of parts to be hereinlater more particularly described, fully claimed and illustrated in the accompanying 45 drawings, in which:

Figure 1 is a perspective view of an article holder constructed in accordance with an embodiment of the invention and applied to a support,

50 Fig. 2 is a vertical sectional view,
Fig. 3 is a rear elevation,

Fig. 4 is a top plan view,

Fig. 5 is a plan view of the blank from which the article holder is formed, and

Fig. 6 is a front elevation of the holder 55 showing the manner of attaching advertising matter thereto.

Referring to the drawings, A designates a support, which may be a wall, side of an ice chest or the like. In order to support 60 an ice pick or like article within convenient reach of the user, I provide a novel holder consisting of a blank sheet of material 5 including side edges 6 and 7 and ends 8 and 9. The side edges 6 and 7 are canted from 65 the end 8 to the end 9.

To provide pockets for the reception of an ice pick, pencil or like implement, the marginal edges of the sides 6 and 7 are rolled back upon the sheet 5 toward each 70 other upon the same side of the sheet. As the portion of the marginal edges adjacent the end 8 is larger than the portion adjacent the end 9 the rolled portions are caused to assume a conical form the entire length of 75 the sides. The conical form is further assisted in view of the fact that the outer wall portions 10 of the pockets are disposed in right angular relation to the ends 8 and 9 so that the device is substantially rectangular 80 in form after the pockets have been provided. The end portions 11 of the pockets adjacent the end 8 provide openings or mouths for the pockets while the other portion or apexes 12 of the conical 85 pockets terminate closely adjacent the end 9. In view of this, when the holder is applied to a support the edge of the end 9 will be positioned in engagement with the support to prevent escape of articles placed in 90 the holder and also to eliminate the use of a separate piece of metal for a bottom. The conical pockets hold the sheet in tapering spaced relation to the support. In this way, 95 the sheet in view of the conical pockets assumes a tapering form to provide a pocket between the conical pockets. Openings 13 are provided in the sheet closely adjacent the conical pockets, fastening means 14 being passed through the openings. As the 100 openings are positioned closely adjacent the inner walls of the pockets, they do not interfere with the insertion of articles either in the conical pockets or the large pocket between the same.

An important feature of this device is that the support provides one wall for the intermediate or large pocket and in view of the

conical pockets, it is not necessary to provide a bottom as the end 9 of the sheet is held in engagement with the support while the end 8 is disposed in spaced parallel relation to the support to provide an opening for the pocket. Ice coupon books, bills, or like articles may be placed in the large intermediate pocket while the conical pockets are constructed to receive ice picks or like implements. The outer surface of the sheet remote from the conical pockets may be provided with advertising matter, said surface providing a large area for advertising matter as it is substantially rectangular and there are no projections or indentations. As shown in Fig. 6, a sheet of advertising matter may be provided with eyelets 15 and secured to the holder by means of fastening means, or the matter may be printed on the holder.

From the foregoing it will be readily seen that this invention provides a novel invention capable of being applied to any desired support to hold various articles and as its construction is simple, its value as an advertising article cannot be estimated.

What is claimed is:—

1. A holder of the character described comprising a blank sheet of material having 30 its side portions convergent from one end to the other of the sheet, said side portions being rolled back upon the sheet to provide conical pockets, the outer walls of said pockets being disposed in right angular relation to the ends of the sheet, the apex of each conical pocket terminating closely adjacent one end of the sheet, said sheet having openings closely adjacent the inner walls

of each pocket, said pockets positioning the last mentioned end of the sheet closely adjacent a support and the remainder of the sheet in tapering spaced relation to the support to provide a tapering pocket between the conical pockets. 40

2. The combination with an ice receptacle, 45 of an ice implement holder consisting of a blank sheet of material having two of its opposed marginal edges coiled upon said sheet in conical formation to provide pockets, said conical pockets holding the intermediate and one end portion of the sheet in spaced relation to the receptacle, and means for securing said sheet to the receptacle whereby a pocket is formed between said conical pockets through the cooperation 50 of the receptacle.

3. The combination with an ice receptacle, 60 of an ice implement holder consisting of a blank sheet of material having two of its opposed marginal edges coiled back upon said sheet toward each other in conical formation to provide pockets, said sheet having an opening disposed closely adjacent each conical pocket for the reception of fastening means, said conical pockets holding 65 the sheet in an inclined position with respect to the receptacle, and fastening means disposed in said openings and securing said sheet to the receptacle, whereby articles may be placed in the pocket formed between the 70 conical pockets without engaging said fastening means.

In testimony whereof I hereunto affix my signature.

CLYDE F. ROBINSON.
